(No Model.)

T. C. BONNETTE.
LAWN SPRINKLER.

No. 461,415.

Patented Oct. 20, 1891.

Attest:

Geo. P. Thomas.

Inventor:

Thomas C. Bonnette
By Jas. W. Thomas

UNITED STATES PATENT OFFICE.

THOMAS C. BONNETTE, OF BAY CITY, MICHIGAN.

LAWN-SPRINKLER.

SPECIFICATION forming part of Letters Patent No. 461,415, dated October 20, 1891.

Application filed April 16, 1891. Serial No. 389,174. (No model.)

To all whom it may concern:

Be it known that I, THOMAS C. BONNETTE, a citizen of the United States, residing at Bay City, in the county of Bay and State of Michigan, have invented certain new and useful Improvements in Lawn-Sprinklers, of which the following is a specification, reference being had to the accompanying drawings.

My invention relates to improvements in lawn-sprinklers, and pertains to that class of sprinklers in which a jet of water under pressure is distributed in the form of a spray over the lawn by rapidly-revolving blades; and the invention consists in the combination, arrangement, and location of the parts, together with the operation of the same, as I shall presently explain in detail, and which will be also explicitly defined in the claims of this specification.

20 The object of the invention is to provide a device of the class mentioned which will be durable and not liable to wear so as to become inoperative in a short time.

Another object of the invention is to provide devices for distributing the water over a semicircular area upon one side of the distributing-point, whereby the water may be distributed from a point near a walk, fence, or building without wetting the same.

30 Another object is to provide devices for sprinkling lawns which may be easily changed for sprinkling either a circular or a semicircular area, as desired, and which is not liable to become clogged or choked up, and which can also be easily manipulated and handled.

My invention is illustrated in the accompanying drawings, in which will be found the same letters of reference indicating like parts throughout the several views.

40 Figure 1 represents a side view in elevation of my improved lawn-sprinkler, partly sectional, and arranged for distributing water over a circular area. Fig. 2 is a vertical section of the same, showing the parts arranged for distributing water over a semicircular area. Fig. 3 is a plan view of Fig. 1. Fig. 4 is a vertical section of the jet-pipe and of the lower support of the distributing-wings. Fig. 5 is a vertical section of the upper support of 50 the distributing-wings. Fig. 6 is a horizontal section of Fig. 1, taken at xx . Fig. 7 is a horizontal section of Fig. 2, taken at yy . Fig. 8

shows the upper portion of Fig. 1 with the distributing-wings in a different position.

a is a casing inclosing a chamber *b*, and this casing is provided with a hose connection *c*, of the usual form, to which is secured a hose *d*, leading from a hydrant or suitable means for obtaining water-pressure, and *e* is a standard arranged to be stuck into the soil of a lawn for supporting the casing. The upper side *f* of the chamber is provided with a short upwardly-projecting delivery pipe or nozzle *g*, having an opening *h* to the chamber, and this nozzle is preferably located slightly to one side of the center of the side *f*, while diametrically opposite this nozzle is arranged an upwardly-projecting stud *i*.

j is a sleeve having a central longitudinal opening *k* arranged to fit over either the nozzle *g* or the stud *i*, as desired, and *l* are curved wings arranged with a downwardly-projecting thin edge or web *m*, centrally located transversely with the upper end of the opening *k*, so as to divide the opening and provide a free exit for the water on both sides of the web against the curved and vertically-inclined concave inner side *n* of the wings.

o is a vertical spindle rigidly secured to the upper side of the web *m* in vertical alignment with the opening *k*, and *p* are braces secured by their lower ends to the part *f*, and, extending above the wings *l*, are secured by their upper ends to a head-piece *q*. This head-piece is provided with openings *r* and *v*, in vertical alignment with the nozzle *g* and the stud *i*, and with either of these openings the upper end *s* of the spindle is engaged, the end of the spindle being first passed into the desired opening from beneath, and then the sleeve is passed downwardly over the nozzle or the stud in alignment with the opening, the spindle being held in position by a bar *t*, which is pivotally secured upon the head *q*, and which when turned across the openings *r* and *v* forms an end bearing for the spindle and prevents a longitudinal movement thereof, a catch *u* being arranged upon the head for engaging with a recess *w* in the end portion of the bar to retain it in position over the openings, but which will disengage for allowing the bar to be turned to free the openings for permitting the removal of the spindle, as shown in Fig. 3.

The spindle being placed in the opening *v*, with the sleeve *j* over the nozzle *g*, as shown in Fig. 1, water under pressure is admitted through the hose to the chamber *b* and 5 through the nozzle into the sleeve against the web *m*, which divides the stream and directs one-half thereof against the concave outwardly-inclined inner surface *n* of each wing *l*, which causes the wings and spindle to revolve rapidly and distribute the water over a circular area in a fine spray, as shown in Fig. 6, the spindle being lifted by the force of the water to bear its end *s* against the bar *t*, which provides a small area for frictional contact, 10 while the lower end of the spindle is retained in place by the sleeve *j* revolving around the nozzle.

It will be seen that by this construction the action of the web *m* is to divide the water 20 column which passes solidly through the nozzle and start each portion or stream on a whirling action, which is accelerated and turned in an outward direction by the inclined surfaces and the rotary motion of the 25 blades, which breaks the stream into minute drops, so that the water is distributed evenly and in a fine spray over a great area, there being no obstruction or reduced orifices to reduce the force or speed.

30 As shown in Figs. 2 and 7, the spindle *o* is placed in the opening *r*, with the sleeve *j* surrounding the stud *i*, and the stream of water then leaving the nozzle is caught by the web *m* as each radial portion thereof passes over 35 the nozzle, and the face of the stream causing the wings to revolve with great rapidity the water is directed outward in a fine and broken spray and distributed over a semicircular area only, the web *m* on passing the nozzle 40 shutting the stream from further contact with the preceding wing, so that one wing only will be acted upon by the water at a time and over the same portion of their revolution, so that each succeeding wing as it passes over the 45 nozzle will distribute the water over the same semicircular area, and by this arrangement the device can be placed near a walk and distribute the water over an area of which the

edge of the walk is the radial line, so that the walk will be left entirely dry, and passers-by 50 will not be annoyed by stray jets or drops of water flying in their pathway, and the same advantage is gained in placing the sprinkler near a building or fence, as the device then will distribute the water over the lawn with- 55 out wetting the adjacent building.

Having described the construction and operation of my improvement, what I claim as new, and desire to secure by Letters Patent, 60 is—

1. The combination of the nozzle for directing the flow of water, a sleeve passed over and projecting beyond the end of the nozzle, a vertical web arranged diametrically across the upper end of the sleeve for dividing the 65 flow of water, and the distributing-wings pivotally mounted to revolve with the said web on a vertical axis above the sleeve and provided with concave and upwardly-inclined under surfaces having their lower portions merging 70 into the lateral surfaces of the web, substantially as set forth.

2. The combination, in a lawn-sprinkler, of the nozzle *g*, the sleeve *j*, passed over the nozzle, the wings *l*, having the outwardly and upwardly inclined surfaces *n* and joined together at their base by a web *m*, secured diametrically across the said sleeve, a spindle *o*, extending above the wings in vertical alignment with the sleeve, and means for supporting the upper end of the spindle, substantially as described. 75

3. In a lawn-sprinkler, the combination of the wings provided at their base with a transverse web *m* and with the upwardly-inclined concave under side *n* and mounted on a centrally-located pivotal support, and a nozzle *g*, located on one side of the said pivotal support, for the purpose set forth, substantially as described. 80

In testimony whereof I hereunto affix my signature in the presence of two witnesses.

THOMAS C. BONNETTE.
